FLAT KNITTING MACHINE

Karl Richard Lieberknecht, Oberlungwitz, Germany, assignor to Kalio, Inc., New York, N. Y., a corporation of New York

Application April 28, 1937, Serial No. 139,571
In Germany April 30, 1936

9 Claims. (Cl. 66—89)

The present invention relates to flat knitting machines, and is more particularly concerned with narrowing mechanisms employing means for preventing engagement between certain of the narrowing points and the corresponding needles at proper times during the knitting operation as, for example, in the knitting of the diamond point toe.

The object of the present invention is to provide improvements in machines of this general character, with a particular view to simplicity, reliability of operation, and arrangement of the parts in such positions as not to interfere with the plain fabric knitting operations. To this end the present invention comprises the machine hereinafter described and particularly defined in the claims.

In the accompanying drawing Fig. 1 is a sectional elevation of so much of a knitting machine as is necessary for an understanding of the present invention; Fig. 2 is a detail rear view of the needle bar and restraining members; Fig. 3 is a view showing the relation of a needle, narrowing point and restraining member at a point in the cycle of an ordinary narrowing operation; Fig. 4 is a view showing the relation of the parts to prevent loop lifting by the narrowing point; and Fig. 5 is a detail view showing the cam roller shifting arrangement for controlling the restraining members.

In the illustrated embodiment of the invention the machine comprises the usual needle bar 6, spring beard needles 8, sinkers 10, knock-over bits 12, and narrowing points 14; all of which are adapted for operation in the usual manner. Mounted at the rear of the needle bar in the middle of each section of the machine is a bearing 16 on which a guide 18 is journaled. A slide 20 is provided for sliding movement in the guide, and carries at its upper end a series of flexing or restraining members 22 to be hereinafter described in detail. The slide is provided with an upper stop 24 which limits its lowermost position. Below the guide 18 the slide is provided with a forwardly extending lug 25, provided with a stop screw 26, which limits the upward movement of the slide. A compression spring 28 bears at one end against the lug, and at the other end against a part of the needle bar, the action of the spring being such as to hold the slide 18 downwardly and yieldingly against the needle bar as shown in Fig. 1. The guide 18 and the slide 20 are mounted in such a manner that the members 22 normally lie below the knock-over

bits 12, and in no way interfere with the normal knitting operation.

The restraining members 22 are automatically operated by means of a shaft 30 which extends throughout the length of the machine and carries a series of flexible plates 32; underlying the several slides 20. Connected with the shaft 30 is a cam lever 34 carrying a cam roller 36 adapted to be operated by cam 38 on the cam shaft 40 of the machine. At proper times under the control of the pattern mechanism the roller 36 is adapted to be shifted into engagement with the cam 38 by means of a lever 42 as shown in Fig. 5. During the normal plain fabric knitting and narrowing operations the plate 32 is not engaged by the slide 20, but when the restraining members 22 are to be brought into operation, the plate 32 is lifted by the cam 38 into such a position that upon downward movement of the needle bar the bottom of the slide 20 strikes the plate 32, thereby causing a relative movement between the restraining members 22 and the corresponding needles.

Each restraining member as shown in Fig. 3 is arranged obliquely with respect to its corresponding needle, and is curved rearwardly at its upper end as indicated at 44. The curved portion 44 and a part of the shank of the restraining member are grooved in the rear face as indicated at 46.

For ordinary narrowing operations, the narrowing points are actuated in the usual manner. From the position of Fig. 3 which illustrates the initial approach of a narrowing point toward its needle, the needles are moved downwardly and forwardly and the narrowing points are dropped into a position slightly in the rear of their needles. The needles are then moved rearwardly so that the beards are covered by the narrowing points, after which the needles and narrowing points are further dropped together to permit the narrowing points to enter the previously formed fabric loops. This sequence of operations and the further operations of loop lifting and transferring are carried out in the usual manner without the intervention of the restraining members.

When the number of narrowing points in effective operation is to be reduced, as in diamond point narrowing, the restraining members are brought into action. The plate 32 is lifted by the cam 38. Therefore, when the needle bar moves downwardly from its position of Fig. 3, the lower end of the slide 20 strikes the plate 32. The upper ends of the restraining members are thus brought yieldingly into engagement with

the shanks of the needles immediately below the beards, but without closing the beards. As the needle bar is then moved rearwardly to bring the needles toward the narrowing points, such 5 of the needles as have been engaged by the restraining members are prevented from being engaged by the narrowing points. The tips of the narrowing points enter the grooves 46 of the restraining members. This relation of the parts 10 is shown in Fig. 4; the needles or narrowing points, or both, being flexed sufficiently by the members 22 to permit this action without damage. The needles, narrowing points, and restraining members are all moved downwardly together 15 into their lowermost position so that the unimpeded narrowing points may enter the loops of the fabric. The loops on those needles which are engaged by the restraining members pass between the needle shanks and the restraining 20 members and under the beards of the needles, and are thus kept out of contact with the narrowing points. The subsequent operations of 25 loop lifting and transferring are carried out by the operative narrowing points in the usual manner.

During the downward movement from the position of Fig. 4 the slide 20 is held in its uppermost position as determined by the screw 26. Downward movement of the slide concurrently 30 with the needle bar is permitted by proper shaping of the cam 38 and also because of the flexibility of the plate 32.

It will be understood that the certain features of the invention in their broader aspects and more 35 particularly those features relating to the construction and arrangement of the supporting and actuating means for the members 22 are not to be limited in their application to the specific embodiment illustrated for controlling the operation of the narrowing points, but may be employed with equal advantage in combination with the needles with or without the assistance of other instrumentalities to cause loops held on the needle shanks selectively to be engaged within or to be 40 cast off over the needle beards.

Having thus described the invention, I claim:

1. In a flat knitting machine having a needle bar, spring beard needles, and narrowing points, restraining members to prevent engagement between certain of the narrowing points and the 50 needles, and means for supporting the restraining members on the needle bar.

2. In a flat knitting machine having a needle bar, spring beard needles, and narrowing points, restraining members to prevent engagement between certain of the narrowing points and the 55 needles, a slide for the restraining members, and a mounting for the slide on the needle bar.

3. In a flat knitting machine having a needle bar, spring beard needles, and narrowing points, restraining members to prevent engagement between certain of the narrowing points and the 60 needles, a slide for the restraining members, a

pivotal mounting for the slide on the needle bar, and means for causing relative movement between the slide and the needle bar to position the restraining members for engagement with the narrowing points.

4. In a flat knitting machine having a needle bar, spring beard needles, and narrowing points, restraining members to prevent engagement between certain of the narrowing points and the needles, a slide for the restraining members, a guide for the slide pivotally mounted on the needle bar, means to maintain the restraining members in an ineffective position below the needles, and automatic means for operating the slide to engage the restraining members with the 10 needle shanks.

5. In a flat knitting machine having a needle bar, spring beard needles, and narrowing points, restraining members to prevent engagement between certain of the narrowing points and the needles, and means for supporting the restraining members on the needle bar, and controlling means operated in timed relation to the needles and narrowing points for actuating the restraining 20 members.

6. In a flat knitting machine having a needle bar, spring beard needles, and narrowing points, restraining members to prevent engagement between certain of the narrowing points and the needles, and means for supporting the restraining members on the needle bar, and means operated from the cam shaft of the machine for actuating the restraining members.

7. In a flat knitting machine having a needle bar, spring beard needles, and narrowing points, restraining members to prevent engagement between certain of the narrowing points and the needles, and means for supporting the restraining members on the needle bar, a cam and cam roller for operating the restraining members, the roller being normally out of engagement with cam, and shifting means for engaging the cam and roller.

8. In a flat knitting machine having a needle bar, spring beard needles, and narrowing points, restraining members to prevent engagement between certain of the narrowing points and the needles, a slide for the restraining members, and a mounting for the slide on the needle bar, a flexible plate below the slide, and automatic means for operating the plate to engage the slide on a 45 downward movement of the needle bar.

9. In a flat knitting machine having a needle bar, spring beard needles, and narrowing points, restraining members to prevent engagement between certain of the narrowing points and the needles, a slide for the restraining members, a guide for the slide pivotally mounted on the needle bar, spring means to maintain the restraining members in an ineffective position below the needles, and automatic means for operating the slide to engage the restraining members with the 55 needle shanks.

KARL RICHARD LIEBERKNECHT.
